US00D962289S

(12) **United States Design Patent** (10) **Patent No.:** **US D962,289 S**
(45) **Date of Patent:** **** Aug. 30, 2022**

(54) **DISPLAY SCREEN WITH ICON**

(71) Applicant: **Google LLC**, Mountain View, CA (US)

(72) Inventor: **Sehee Lee**, Brooklyn, NY (US)

(73) Assignee: **GOOGLE LLC**, Mountain View, CA (US)

(**) Term: **15 Years**

(21) Appl. No.: **29/794,739**

(22) Filed: **Jun. 15, 2021**

Related U.S. Application Data

(63) Continuation of application No. 29/717,993, filed on Dec. 20, 2019, now Pat. No. Des. 926,816, which is a continuation of application No. 29/643,569, filed on Apr. 10, 2018, now abandoned.
